UNITED STATES PATENT OFFICE.

AUGUST ZACHARIAS, OF MINNEAPOLIS, MINNESOTA.

AUXILIARY HEATER.

Application filed November 3, 1923. Serial No. 672,525.

To all whom it may concern:

Be it known that I, AUGUST ZACHARIAS, a citizen of the United States, residing at Minneapolis, in the county of Hennepin and State of Minnesota, have invented certain new and useful Improvements in Auxiliary Heaters; and I do hereby declare the following to be a full, clear, and exact description of the invention, such as will enable others skilled in the art to which it appertains to make and use the same.

My present invention provides an extremely simple and highly efficient stove or heater especially adapted to be made at low cost from sheet metal and especially well adapted for use in connection with an oil or gas burner. Generally stated, the invention consists of the novel devices and combinations of devices hereinafter described and defined in the claims.

From a broad point of view, the improved stove or heater may be made in different forms and, of course, in different sizes, but the structure is such that it naturally adapts itself to a rectangular formation and for the making of heaters for use in school houses, office buildings, factories, garages, and for the heating of dwellings not equipped with a furnace; but the said heater, when provided with a surrounding jacket or shelf, will make a highly efficient hot air furnace. The stove or heater illustrated in the accompanying drawings, wherein like characters indicate like parts throughout the several views, is such as will be found efficient and desirable for the uses first above noted.

Referring to the drawings:

Fig. 1 is a perspective showing the improved heater;

Fig. 2 is a transverse vertical section taken on the line 2—2 of Fig. 1;

Fig. 3 is a front to rear vertical section taken on the line 3—3 of Fig. 1, some parts being broken away;

Fig. 4 is a horizontal section on the line 4—4 of Fig. 2;

Fig. 5 is a horizontal section on the line 5—5 of Fig. 2; and

Fig. 6 is a perspective showing the oil drip pan removed from the heater.

The outer shell of the heater, as shown, is a vertically elongated rectangular structure made up of laterally spaced side plates 7, a front plate 8, a back plate 9, a bottom plate 10, and a pyramidal top plate 11,

which plates are tied together by corner angles 12 riveted or otherwise rigidly secured thereto with tight joints. This outer shell is supported by legs 13, so that the bottom of the shell is above the floor. A short distance above its bottom, the shell is provided with a horizontal sheet metal plate 14 that extends from side to side and to the front thereof, but at its rear edge is provided with a downturned portion 14' that is spaced from the back plate 9 and extends down to the bottom plate 10, (see Figs. 2 and 3). Above the horizontal plate 14, the shell is provided with another horizontal plate 15 that also extends from side to side and from the front plate of the shell, but terminates short of the back plate 9 so as to leave a rear flame passage 16 that is the full width of the interior of the shell. Between the plates 10 and 14 there is thus formed a drip pan chamber 17, and between the plates 14 and 15 is formed a primary combustion chamber 18. At their fronts, the chambers 17 and 18 are primarily open but normally closed by hinged doors 19 and 20, the former of which is provided with adjustable air-controlling dampers 21. The plate 14, at its center, is provided with a large air passage 22 over which is placed a burner base 23 shown as equipped with two oil burners 23'. The burners 23' are shown as supplied with oil, such as kerosene or distillate, through branch pipes 24 equipped with valves 24' and connected to a main oil supply pipe 25 that leads from a suitably supported elevated oil supply tank 26.

To catch any oil dripping from the burners, I provide a drip pan 27 shown as provided with a hopper-like bottom having a drain passage 27' at its lowest point. This pan is removably supported on flanges 28, preferably small angle bars secured on the side plates 7. When this drip pan is positioned, its drain passage 27' stands over a funnel-like drain nipple 29 formed on or secured to the bottom plate 10. The numeral 30 indicates an oil-receiving receptacle placed below the drain nipple 29.

Adjacent to but preferably slightly spaced from the side plates 7 of the main shell is a pair of laterally spaced main air intake ducts 31. These air ducts 31 are of shallow but wide rectangular cross section and they extend from the front plate 8 to the back plate 9 in front to rear direction and in a vertical direction extend from

points below the bottom plate 10 up through said plate 10 and the plates 14 and 15 and through the bottom plate of a horizontal air duct 32, which latter extends through 5 the laterally spaced side plates 7 but is spaced from the front and rear plates 8 and 9 so as to leave short vertical flame passages 33. Spaced above the transverse horizontally extended air duct 32 is a similar 10 front to rear air duct 34 that extends through the front and rear plates 8 and 9 but is spaced from the side plates 7 so as to form short vertical flame passages 35.

Spaced above the air duct 34 is a second 15 transverse horizontally extended air duct 36 that is rectangular in vertical cross section and extends through the side plates 7 but is spaced from the front and rear plates 8 and 9 to afford short front and rear air passages 20 37.

Spaced above the second transverse air duct 36 is a second front to rear air duct 38 that extends through the front and rear plates 8 and 9 but is spaced from the side plates 7 so as to form short laterally spaced 25 air passages 40. A large but vertically short air tube 41 centrally connects the air ducts 32 and 34; a similar air tube 42 centrally connects the air ducts 34 and 36; and another similar air tube 43 centrally connects 30 the air ducts 36 and 38. It will now be seen that the air ducts 32 and 36 extend at right angles to the air ducts 34 and 38 and that the flame passage takes a rectangular winding course around all of these air ducts.

35 A smoke stack 44, shown as equipped with a damper 45, leads upward from the pyramidal dome or top plate 11 for carrying off the products of combustion. Preferably, hot air ducts 46 extend through the top 40 plate of the air duct 38 and through the top plate 11.

In actual practice, this heater has been found to be of exceedingly high efficiency. The hot flames or hot products of combustion 45 from the burner are caused to take a long tortuous rectangular course around the numerous and long tortuous air ducts, so that nearly all of the heat produced by the combustion may be transferred to the air and the products of combustion discharged 50 at very low temperature with a resulting high economy in the use of the fuel. The coldest air will be drawn from the vicinity of the floor up through the primary air 55 ducts 31 and this air, as it is heated, will be joined by other drafts of relatively cold or cool air drawn in through the horizontal air ducts and the resulting stream of air will be carried centrally upward through 60 the central air passage afforded by the tubes 41, 42 and 43. All of the air ducts, it will be noted, are surrounded by flame passages, so that a very large amount of heat-radiating surface is afforded. If the air tubes 46 65 were not provided or if closed, the hot air

would all be discharged out through the upper air duct 38, but when the air ducts 46 are provided and are of a sufficient size or number to readily take care of the maximum flow of hot air, most of the hot air will be 70 delivered therethrough. The transverse air ducts 32, 34, 36, and 38 have this peculiar function that they may act either as cool air intake ducts or as hot air outlet ducts. As long as the hot air finds a ready escape upward, they will act as air intake ducts, but when the flow of hot air is more rapid, so that a choking action is produced in the upper passages, then they will act more or less as hot air outlet ducts. In this respect, 80 the said air ducts are self-regulating and, in practice, take care of the heating conditions in the most satisfactory manner.

So far as my invention is concerned, any suitable form of oil or gas burner may be 85 employed and, in fact, a coal or wood burner may be employed when desired. Nevertheless, the above described structure is peculiarly adapted for use of oil or gas burners. The term "oil or gas burner" is herein used synonomously to indicate a fluid fuel burner.

What I claim is:

1. A heater comprising a casing, transverse air ducts extended through said casing and interconnected by vertical air tubes, a primary combustion chamber in the lower portion of said casing, and an oil burner in said combustion chamber, the sides of said air ducts being spaced from the sides of the casing to afford tortuous flame passages extended from said combustion chamber upward and between the sides of the casing and air ducts and under and over said transverse air ducts and terminating at its upper extremity in an outlet stack.

2. In a heater, a casing provided at its lower portion with a primary combustion chamber and above said combustion chamber having transverse air ducts that extend in intersecting vertical planes and are interconnected vertically, and the sides of said air ducts being spaced from the sides of the casing to afford flame passages extended upward from said primary combustion chamber and between the sides of the casing and air ducts and under and over said transverse air ducts and terminating in an outlet stack.

3. The structure defined in claim 2 in further combination with laterally spaced primary air ducts extended through the bottom of said casing and connected to the first of said transverse air ducts.

4. The structure defined in claim 2 in further combination with laterally spaced primary air ducts extended through the bottom of said casing and connected to the first of said transverse air ducts, and hot air outlet tubes extended from the uppermost of

said transverse air ducts upward through the top of said casing.

5. A heater comprising a rectangular casing provided in its lower portion with a primary combustion chamber, transverse rectangular horizontal air ducts extended through said casing at different elevations, said air ducts being alternately extended in different intersecting vertical planes and 10 at their sides spaced from the walls of said casing to afford flame passages extended upward from said primary combustion chamber and between the sides of the casing and air ducts and under and over said 15 air ducts, said transverse air ducts being interconnected by vertical air tubes.

6. A heater comprising a rectangular casing provided in its lower portion with a primary combustion chamber, transverse rectangular horizontal air ducts extended through said casing at different elevations, said air ducts being alternately extended in different intersecting vertical planes and at their sides spaced from the walls of said

casing to afford flame passages extended upward from said primary combustion chamber and between the sides of the casing and air ducts and under and over said air ducts, and primary air intake ducts that extend from the lowermost transverse air duct 30 downward in said casing along the sides of said primary combustion chamber and open through the bottom of said casing.

7. The structure defined in claim 6 in which said transverse air ducts are interconnected by vertical air tubes centrally located 35 within the casing.

8. The structure defined in claim 6 in which said transverse air ducts are interconnected by vertical air tubes centrally located 40 within the casing, and in further combination with a foul air stack leading from the upper portion of said casing, and air tubes extended from the uppermost transverse air duct through the top of said casing. 45

In testimony whereof I affix my signature.

AUGUST ZACHARIAS.
